Primary Examiner—Adir Aronovich(74) *Attorney, Agent, or Firm*—Plumsea Law Group, LLC(57) **CLAIM**

The ornamental design for a guitar pedal, as shown and described.

DESCRIPTION

FIG. 1 is a perspective view of a guitar pedal showing our new design;

FIG. 2 is a top plan view thereof;

FIG. 3 is a front elevational view thereof;

FIG. 4 is a side elevational view, the opposite side elevational view being a mirror image thereof; and,

FIG. 5 is a rear elevational view thereof.

The broken line showings of the knobs, buttons and display on the top panel, the line along the housing body, the circle in the side view, and the features on the rear panel are for illustrative purposes only and form no part of the claimed design.
